UNITED STATES PATENT OFFICE.

LOUIS E. PIERPONT, OF CAMBRIDGE, NEBRASKA.

VAPOR-BURNER.

SPECIFICATION forming part of Letters Patent No. 380,404, dated April 3, 1888.

Application filed October 7, 1887. Serial No. 251,744. (No model.)

To all whom it may concern:

Be it known that I, LOUIS E. PIERPONT, a citizen of the United States, residing at Cambridge, in the county of Furnas and State 5 of Nebraska, have invented new and useful Improvements in Vapor-Burners, of which the following is a specification.

My invention relates to improvements in vapor-burners; and it consists in the peculiar 10 construction and combination of devices that will be more fully set forth hereinafter, and particularly pointed out in the claims.

In the accompanying drawings, Figure 1 is a vertical sectional view of a vapor-burner 15 embodying my improvements. Fig. 2 is partly a top plan view of the same and partly a horizontal section.

A represents a cap which is screwed to the top of the stand-pipe B by which the gasoline 20 enters the generator.

C represents a generator which is hemispherical in shape and is concave on its upper side, as shown. Formed in the upper edge of the said generator is an annular duct, D, which 25 communicates with the upper end of the cap A on one side. A duct, E, formed in the generator communicates with the duct D at a point diametrically opposite the cap A. This duct extends downward to the center of the 30 generator, as shown.

F represents a vertical valve-seat, which is tubular in form and projects upwardly through a central opening in the bottom of the generator. This valve-seat communicates with 35 the lower end of the duct E.

G represents a needle-valve which is screwed into the seat F. The said needle-valve has a stem, H, which extends downward below the generator for a suitable distance and is adapted 40 to be turned in the valve-seat by means of a suitable handle or wheel attached to the lower end of its stem, so that the conical point of the valve may be caused to entirely close the conical opening in the upper end of the valve-seat, 45 or to open the same to the desired extent.

I represents a clamping-nut which works on the threaded portion of the needle-valve below the tubular valve-seat, and is adapted to be screwed up against the lower end of the 50 valve-seat, so as to secure the needle-valve at any desired adjustment therein.

The needle-valve and its stem are provided with a vertical central bore or opening, K, which extends entirely through the same, and 55 is thereby adapted to cause a current of fresh

air to pass upward through the needle-valve and be discharged into the center of the generator from the point of the valve.

The operation of my invention is as follows: Initial heat is applied to the burner in the 60 usual manner and the gasoline is caused to flow from the cap A through the ducts D and E in the generator to the tubular valves E F, and as the gasoline passes through the said ducts it becomes heated by contact therewith 65 and vaporized and the vapor escapes upward through the opening in the upper end of the valve seat F surrounding the needle-point, where it is ignited. The constant current of fresh air which passes upward through the 70 needle-valve is caused to commingle with the vapor at the point of the needle-valve, and thereby promote combustion. It will be seen that the air is thus supplied to the base of the flame at a point where it renders the combustion 75 more nearly perfect, and hence a maximum proportion of the gas is consumed in the flame, and an economy of the gasoline is thereby effected.

Having thus described my invention, I 80 claim—

1. A vapor-burner having the needle-valve provided with an opening which communicates with the outer air and extends to the point of the valve, for the purpose set forth, substantially as described. 85

2. The combination of the generator, the valve-seat therein, the ducts to supply vapor to the said valve-seat, and the needle-valve arranged in the valve-seat and having the opening extending to its point, and thereby adapted to supply air to the base of the flame, substantially as described. 90

3. The combination, in a vapor-burner, of the generator C, having the valve-seat F at 95 its lower side, and the ducts D and E, communicating with the stand-pipe, and the valve-seat to supply vapor to the latter, and the needle-valve arranged in the valve-seat and having the opening communicating with the outer air and extending to its point to supply air to the base of the flame, substantially as described. 100

In testimony that I claim the foregoing as my own I have hereto affixed my signature in presence of two witnesses.

LOUIS E. PIERPONT.
